SPECIAL CHARACTER AND AMOUNT
PRINTING MECHANISM

Herbert E. Brown, Detroit, Mich., assignor to Burroughs Adding Machine Company, Detroit, Mich., a corporation of Michigan

Application June 26, 1941, Serial No. 399,803

9 Claims. (Cl. 101—93)

This invention relates to a calculating machine and is particularly concerned with a safeguard printing means therefor, whereby the machine, when printing amounts on certain papers or documents, particularly checks or other negotiable instruments, may also print, to the left of and adjacent to the amount, one or more characters or symbols to hinder or prevent subsequent alteration of the printed amount by the adding of numerals to the left of the originally printed amount.

In some prior calculating machines having, for each numeral order of the machine, a type carrier carrying all of the type for the respective numerical order, each type carrier in orders above a certain numerical order, such as the units of dollars order, has been provided with an extra safeguard printing character type in a position adjacent to the "0" type, and means have been provided for so controlling the positions of those type carriers which, during the operation of the machine, have not been moved to positions for printing digits other than "0", that the safeguard character type are positioned at the printing line in orders above the highest order of the amount to be printed, whereas the "0" type are positioned at the printing line in lower orders in which the type carriers are not positioned for printing digits other than "0". As the type carriers are connected with the differential actuator members by which the amounts printed are entered into or taken from the calculating or registering mechanism of the machine, such special control of the type carriers for the selection of the "9" and safeguard character type for printing in orders where digits from 1 to 9 are not printed has required that the connection between the type carriers and the differential actuator members be so constructed as to permit of relative movement between the type carriers and the differential actuator members and to permit of the shifting of the type carriers between their "0" printing and safeguard character printing positions without moving the corresponding differential actuator members. In machines in which such relative movement between the differential actuator members and the type carriers has not been required also for other purposes, such as for effecting tens-transfers in the registering or calculating mechanism, the provision for such relative movement between the type carriers and the differential actuator members has been an undesirable complication of the machine construction. The present invention proposes to provide for safe-

guard printing in calculating machines without requiring the provision of the extra safeguard printing characters on each of a substantial number of the type carriers of the machine, and 5 also proposes to provide safeguard printing without requiring provisions to permit of relative movement between the type carriers and the differential actuator members and without special control of the regular type carriers carrying the digit type for the several numerical orders of the machine.

An object of the invention is to provide an improved safeguard printing means for calculating machines.

15 A further object of the invention is to provide a safeguard printing means for calculating machines employing a safeguard printing type member operated and controlled to print in all safeguard printing operations of the machine 20 immediately to the left amounts with varying numbers of numerical orders.

25 A further object of the invention is to provide an improved safeguard printing means for calculating machines in which, for the purpose of permitting the printing of the safeguard characters in line with the amount, use is made of the case-shift movement of the platen instead of special movement and control of the type carriers of the various numerical orders of the machine.

30 Further objects of the invention will appear from the following specification and drawings illustrating one embodiment of the invention and in which:

35 Figure 1 is a left-side elevation of a machine with the invention applied thereto;

Fig. 2 is a right-side elevation of a detail of the mechanism shown in Fig. 1;

40 Fig. 3 is a perspective view, from the upper left rear corner of the machine, showing a portion of the printing mechanism and illustrating the application of the invention thereto;

45 Fig. 4 is a perspective view, from the upper left front corner of the machine, of a portion of the mechanism shown in Fig. 3;

Figs. 5 and 6 illustrate, by way of example, samples of work performed by the machine illustrated in Figs. 1 to 4.

50 The invention is shown applied to a machine of the well-known Burroughs-Moon-Hopkins type, the general features of which are disclosed in Hopkins Patent No. 1,336,904. It is to be understood, however, that the invention may also be applied to other types of machines.

General features

The illustrated machine is a typewriting and ten-key calculating machine having a typewriter keyboard, the type keys 20 of which operate typewriter type actions, parts of which are indicated by reference numeral 21, to cause the typewriter type to strike against a platen P supported on a traveling paper carriage C. The machine also has a calculating keyboard indicated generally by the reference numeral 25, comprising ten numeral keys and the required calculating function control keys by which the calculating mechanism of the machine may be conditioned to perform the necessary calculating operations with the amounts entered therein by means of the numeral keys. The calculating mechanism includes a series of differential actuator racks 30 cooperating with registering mechanisms 35. The forwardly extending portions of the differential actuator racks 30 form type bars 31 in which the calculating machine type are carried, the stems 32 of the individual type 33 being vertically movably supported in the type carriers 31 so that the type positioned along the printing line may be struck against the platen P by a line of printing hammers 34, one of which is shown in Fig. 1.

The calculating mechanism of the machine is operated from a main drive shaft 40 which may be operated manually by means of a hand crank (not shown), but is preferably operated by means of an electric motor 41 through a clutch mechanism 42 controlled by a motor bar 43 as well as by certain of the function control keys above mentioned. The driven shaft 45 of the clutch has fixed thereon a crank 46 to which is connected one end of a link 47 connected at its other end to a crank 48 on the shaft 40. Upon depression of the motor bar 43 or one of the function control keys above mentioned, the motor 41 is caused to give the calculating mechanism one or more cycles of operation, in each of which the main shaft 40 is rocked first clockwise from its Fig. 1 position and then turned counterclockwise to its Fig. 1 position. The drive mechanism, including the clutch 42, may be of the construction disclosed in detail in Hopkins Patent 1,025,698.

During an amount or total printing operation of the machine the differential actuator racks 30 are moved forwardly, that is, to the right in Fig. 1, during the clockwise movement of the shaft 40, as viewed from Fig. 1, to positions where those type in the type carriers 31 which correspond to the amount or total to be printed are positioned in vertical alignment with the printing line of the platen P, after which the hammers 4 are driven against the stems 32 of the type at the printing line to drive such type against the platen P, and, at a given point in the return of the shaft 40 counterclockwise to its Fig. 1 position, the actuator racks 30 and type carriers 31 are returned rearwardly to their normal positions. The "0" type at the printing line in orders higher than the highest order to be printed are not struck against the record material by their hammers 4, as the machine includes "0"-print eliminating means such as that disclosed in Hopkins Patent No. 1,336,904, and described particularly on pages 18 and 19 thereof. In the normal position of the parts the "0" type 33 of the type carriers are positioned along the printing line of the platen P.

The typewriter mechanism of the machine comprises a platen shifting means by which the platen P may be shifted forwardly from its normal position shown in Figs. 1 and 3, indicated in dot-dash

lines at A in Fig. 4, to the position indicated in dot-dash lines at B in Fig. 4, accordingly as it is desired to print from either one or the other of two types carried by each of a plurality of typewriter type-levers. When the platen is in its normal position A of Fig. 4, the printing line is in line with the line of "0" types on the type carriers 31 in their normal positions. When the platen is in the forward shifted position B of Fig. 4, the printing line is forwardly of the line of "0" types on the type bars 31 in their normal positions.

The platen shaft 50 (Fig. 3) is journaled in the platen frame side plates 51 (Figures 1 and 3), which are connected together in laterally spaced relation by suitable cross members, one of which is indicated by 52 in Fig. 3. The forwardly projecting ends of the platen frame side plates 51 rest on roller studs 53x supported on the inner sides of the side plates 53 of the traveling carriage frame and the cross member 52 (Fig. 3) of the platen frame is pivotally suspended by links 54 from a cross shaft 55 of the traveling carriage frame.

The shifting of the platen from its rearward amount printing position A of Fig. 4 to its forward typewriting position B is effected by depression of a shift key 60, the key lever 61 of which is pivotally supported at its rearward end in the machine frame and connected intermediate its ends to the lower end of a link 62, which is connected at its upper end (Fig. 3) to the forward end of a lever 63 secured to a shaft 64, to which there is also secured a lever 65 which projects into an opening formed in a lever 66 intermediate the ends of the latter. The lever 66 is pivoted at its left end as viewed from the front of the machine on a stud 67 carried by the machine frame, and carries at its right end as viewed from the front of the machine (its upper left end as viewed in Fig. 3), a roller 68 which bears against the rear side of the cross member 52 of the platen frame. The platen frame is normally urged to its rearward position by the usual spring means 69, but upon depression of the shift key 60 the link 62 is drawn downwardly and rocks the lever 63, the shaft 64 and the lever 65 and lever 66 clockwise as viewed in Fig. 3 to shift the platen to the forward position B of Fig. 4. The parts may be held in this position by the usual shift-key latch until the latter is released upon completion of the typing and the platen is returned rearwardly by the usual spring, above mentioned, to the rearward position A of Fig. 4.

The platen occupies its normal rearward position A of Fig. 4 during the printing of amounts by the calculating machine printing mechanism. If safeguard characters are to be printed to the left of the amount printed by the calculating machine printing mechanism, the safeguard character type is automatically moved to a position immediately in front of the "0" type of one or more of the type carriers 31 located immediately to the left of the highest order of the amount printed, the platen is automatically shifted forwardly from position A to position B of Fig. 4, whereupon the safeguard character type is struck against the platen, after which the parts are restored to normal.

Safeguard printing means

The safeguard character printing means are operated from the shaft 40 during the return stroke of the latter (counterclockwise in Fig. 1) after the printing hammers 34 have been fired near the end of the forward stroke of the shaft

40 (clockwise in Fig. 1), but prior to the return of the differential actuator racks 30 and type carriers 31 rearwardly in the cycle of operation in which the amount is printed.

An arm 70 (Figs. 1 and 2) secured on the shaft 40 carries a shaft 71 which, during the forward stroke of the machine cycle, moves counterclockwise from the full-line position to the dot-dash line position of Fig. 2 and, during the return stroke of the cycle, returns to the full-line position. A pass-by pawl 72 pivoted on a stud 73 on a link 74 carries on its forwardly projecting end a stud 75 connected by a spring 76 to a stud 77 which is carried by the link 74 and projects through a slot in the pass-by pawl 72. The pass-by pawl is thus urged counterclockwise in Fig. 2 (clockwise in Fig. 1) to the position shown in Fig. 2 where the shoulder 78 of the pawl 72 is in the path of the shaft 71. During the forward stroke of the machine cycle with the pawl 72 in the position of Fig. 2, the shaft 71 cams the pawl 72 clockwise against the tension of the spring 76, but at the beginning of the return stroke the shaft 71 engages the shoulder 78 and drives the pawl 72 and thus also the link 74 rearwardly, or to the left in Figs. 1 and 3. Near its rearward end the link 74 is guided on a fixed stud 80 (Fig. 1) and is connected to one end of a spring 81 which urges the link 74 forwardly.

The forward end of the link 74 is connected to the lower arm of a lever 82 pivoted on a stud 83 carried by a fixed member of the machine. The upper end of the lever 82 is slotted to receive a stud 84 on one arm of a crank 85 pivoted on a stud 86 carried by the main longitudinal portion of an irregularly shaped slide 87. A spring 88 connected to a stud on the crank 85 and to a stud on the slide 87 urges the crank 85 clockwise to its normal position of Fig. 3. The main longitudinal portion of the slide 87 is provided with studs 89, 90 and 91, by which it is slidably supported in slots in a supporting member 92 secured to a stationary portion of the machine at 93. A spring 90a connected between the stud 90 on the slide 87 and a stud on the member 92 tends to urge the slide 87 forwardly though the spring 81 is of sufficient strength that normally, acting through the link 74, lever 82 and crank 85, it is capable of holding the slide 87 in its normal rearward position as illustrated in Figs. 1 and 3. The portion of the screw stud 91 which bears in the slot in the member 92 is eccentric with respect to the portion of said stud engaging in the slide 87 so that the front portion of the slide 87 may be adjusted vertically by rotating the stud 91.

The forward end of the slide comprises a front transverse portion 87a joined through a longitudinal portion 87b to a rear transverse portion 87c which is joined to the main longitudinal portion of the slide. The forward arm of the crank 85 carries a roller 95 positioned above and in engagement with a roller stud 96 carried by a lever 97 pivoted on a stud 98 carried by the forward transverse portion of the slide 87. The spring 88 is of sufficient strength to hold the roller stud 96 in the normal position shown in Fig. 3 against the tension of a spring 99 which is connected to studs on the lever 97 and the front transverse portion 87a of the slide 87 to urge the lever 97 clockwise as viewed in Fig. 3. A slot in the lever 97 receives a stud 100 carried by one arm of a crank 101 pivoted on a stud 102 carried by the front transverse portion 87a on the slide 87. The other arm of the crank 101 is slotted to

receive a stud 103 projecting through a slot 103a formed in the portion 87a of the slide 87 and secured in a slide 104 which is slidably mounted on the portion 87a by means of the stud 103 and a stud 105 also secured in said slide 104 and extending through another slot in the portion 87a. The left end of the slot 103a as viewed from the front of the machine (right end as seen in Fig. 3) forms a limit fixing the normal position of the slide 104 and of the lever 97 and stud 96.

At its right-hand end as viewed from the front of the machine the slide 104 has a guide 106 in which the stem 107 of the safeguard character type member 108 is vertically slidably received. A stud 109 secured in the stem 107 of the safeguard character type member 108 projects through a slot in the side of the guide 106 and into a slot in the end of one arm of a crank 110 pivoted on a stud 111 secured in the slide 104. The crank 110 is urged clockwise as viewed in Fig. 4 by a spring 112 so as normally to hold the type member 108 in its lower position.

The slide 87 and parts carried thereby operate as follows: When the link 74 is pulled rearwardly at the beginning of the return stroke of the machine cycle, the lever 82 is rocked clockwise in Figs. 1 and 3 and moves the stud 84 forwardly. During the initial portion of this forward movement of the stud 84 the spring 88 holds the crank 85 against counterclockwise movement and, aided by the spring 90a, causes the slide 87 to move forwardly until the slide 87 reaches the limit of the forward movement permitted by its stud and slot connections with the member 92. During this movement of the slide 87 the special character type member 108 is moved to the position shown in dot-dash lines at 108a in Fig. 3 where its rear edge is slightly forward of the front edges of the "0" types of those type carriers which are in their normal "0" positions.

Continued rearward movement of the link 74 and clockwise movement of the lever 82 then causes the crank 85 to be rocked counterclockwise in Fig. 3, thus raising the roller stud 95. The spring 99 causes the lever 97 to rock clockwise in Fig. 3 and the stud 96 to follow the stud 95 in contact therewith. The lever 97 acting on the stud 100 of the crank 101 causes the latter to rock counterclockwise in Fig. 3 and shift the slide 104 and the safeguard printing type member 8 to the right as viewed from the front of the machine (to the left in Fig. 3) until the slide 104 is stopped by engagement of the guide 106 thereon against the side of the highest order type bar 31 which has been moved forwardly of its "0" printing position in the amount printing operation. This movement shifts the safeguard printing type member from the position indicated at 108a in Fig. 3 to a position such as that shown in Fig. 4 and indicated in dot-dash lines at 108b in Fig. 3, where the safeguard printing characters are immediately to the left (as viewed from the front of the machine) of the highest order of the amount printed.

In the event that only the cents and/or dimes orders type bars 31 have been moved forwardly of their "0" printing positions to print an amount less than one dollar, the safeguard printing type member 108 is prevented from moving all the way over to a position adjacent the dimes type bar 31 and, instead, is stopped in a position immediately to the left, viewing the machine from the front, of the units of dollars type bar 31, at which point the stud 103 engages the end of the slot in the front transverse portion 87a of the

slide 87. Though neither the units of dollars type bar 31 nor any higher order type bars 31 are moved forwardly of their "0" printing positions, a "0" is caused to be printed in the units of dollars order at the same time that printing is effected in the two next lower orders by the usual means which, in machines of the illustrated kind, cause printing to be effected in the cents, dimes and units of dollars orders in every total-taking and/or amount printing operation of the machine even when the total or the amount is less than one dollar. Of course, this well-known mechanism and the length of the slot limiting the movement of the stud 103 and type member 108 to the right, viewing the machine from the front, may be modified as desired so as to permit the printing of ciphers in orders in which other numerals are not printed in any desired minimum number of the lowest numerical orders of the machine.

The rearward movement of the link 74 and clockwise movement of the lever 82 also effects the automatic shifting of the platen from the amount printing position A of Fig. 4 to the typing position B, where the printing line of the platen is forwardly of the forward ends of the type bars 31 which are in their normal "0" positions and immediately above the printing position of the safeguard printing type member 108. For this purpose the lever 82 has a forward arm 115 projecting above one arm of the lever 116 pivoted intermediate its ends at 117 to a fixed member of the machine and having a second arm engaging under the rear end of a lever 118 which is pivoted intermediate its ends at 119 to a fixed member of the machine. The forward arm of the lever 118 is connected to one member 120 of a linkage comprising a second member 121 having stud and slot connections with the member 120 and also connected to the member 120 through a spring 122 which normally yieldingly holds the linkage 121, 122 in a contracted condition. The upper end of the link member 121 has a stud and slot connection with the lever 63 so that during the initial portion of the rearward movement of the link 74 and clockwise movement of the lever 82, the lever 116 is rocked counterclockwise and the lever 118 is rocked clockwise and, through the yielding linkage 120-122, rocks the lever 63, shaft 64, and levers 65 and 66 clockwise to shift the platen to the forward typing position B of Fig. 4.

After the platen has reached the forward position and the safeguard printing character type member 108 has reached its printing position immediately to the left of the highest order of the amount printed and in front of the next higher order bar or bars 31, the safeguard printing type member 108 is driven against the platen by a hammer 125 also actuated by the rearward movement of the link 74 and clockwise movement of the lever 82. For this purpose the forward end of the lever 118 has a lateral lug 126 projecting above a pawl 127 pivoted on a stud 128 on a stationary portion of the machine and having an eccentric stud 129 which is normally held in contact with the forward end of a lever 130, also pivoted on the stud 128, by a spring 131 connected between the stud 129 and the stud on the lever 130. The rearward end of the lever 130 carries a stud 132 which engages in the rearward slotted end of a lever 133 pivoted on a stud 134 carried by a fixed portion of the machine. The forward end of the lever 133 is connected through a link 135 with the hammer 125 which is pivoted on a stud 136 secured in a fixed portion

of the machine. When the lever 118 is rocked clockwise in Fig. 3 by the rearward movement of the link 74 and clockwise movement of the lever 82, the lug 126 engages and depresses the forward end of the pawl 127 which, through the spring 131, rocks the lever 130 and thereby the lever 133 clockwise to pull the link 135 downwardly and swing the printing hammer 125 against the lower end of the stem 107 of the printing type member 108 to drive the latter against the platen. The hammer 125 is of sufficient length to strike the stem 107 of the safeguard printing type member 108 in any of the positions along the printing line to which the type member 108 may be moved. It will be seen that, regardless of the number of numerical orders above a chosen minimum number of numerical orders in any amount printed by the calculating mechanism in any safeguard printing operation, the special safeguarding printing type member is always moved from its normal position in Fig. 3 to the appropriate position in vertical alignment with the printing line of the platen, which has been shifted forwardly after the printing of the amount, so that the safeguard characters will be printed immediately to the left of the amount which was printed before the forward shifting of the platen.

Thus, during the forward stroke of the machine cycle while the shaft 71 swings clockwise, the type bars 31 are advanced to positions corresponding to an amount to be printed and, while the platen is in its normal rearward position, the amount is printed, and then, during the return stroke of the machine cycle and while the shaft 71 swings counterclockwise, the link 74 is moved rearwardly and lever 82 is swung clockwise to shift the platen forwardly and shift the safeguard printing type member forwardly and then laterally to a position in lateral alignment with and immediately to the left of the highest order of the amount printed after which, during further rearward movement of the link 74 and clockwise movement of the lever 82 and while the linkage 120-122 expands against the tension of spring 122, the hammer 125 is operated to strike the type 108 against the platen and imprint the safeguard character or characters on the paper.

The various parts involved are so proportioned that printing of the safeguard characters is effected prior to the time that the indexed type bars 31 being restored are moved from their "1" to their "0" position and while the slide 104 and type member 108 are held in the correct lateral position by the highest order type bar 31 which was moved forwardly of its "0" position for printing the amount.

After the hammer 125 has driven the type member 108 against the platen, the continuing return movement of the shaft 71 (clockwise in Fig. 2) carries said stud away from behind the shoulder 78 of the pawl 127, whereupon the spring 81 returns the link 74 forwardly and the lever 82 counterclockwise to the normal position of Fig. 1.

In the return forward movement of the link 74 and counterclockwise movement of the lever 82, the printing hammer 125 and levers 133-130 are restored to normal by gravity aided by a spring 137 connected to the stud 132. The platen and platen frame, levers 66 and 65, shaft 64, lever 63 and linkage 120, 121 and levers 118 and 116 are restored to normal by the previously mentioned spring, which urges the platen frame to its rearward position. During the initial portion of the

counterclockwise return movement of the lever 82, the crank 85 is rocked clockwise in Fig. 3 to depress the roller stud 96 and rock the lever 97 counterclockwise and the crank 101 clockwise to restore the slide 104 to its normal position on the portion 87a of the slide 87 and return the safeguard printing type member to the position indicated at 108a in Fig. 3. During this movement of the parts 85, 97, 101 and 104, the springs 88 and 90a cause the slide 87 to be held in its forward position, but when the stud 96 is stopped by engagement with the upper edge of the portion 87c and slide 87, the further counterclockwise movement of the lever 82 and rearward movement of the stud 84 cause the slide 87 to be returned rearwardly against the tension of the spring 90a to the normal position of Fig. 3.

It will be noted that the safeguard character type 108 in its normal position shown in full lines in Fig. 3 is not only out of the path of forward movement of the highest order type bar 31 but is also rearward of the line of the forward ends of the type bars 31 so that it will not interfere with the operation of the typewriter type levers, some of which must swing to a position across the front ends of the type bars 31 to the typewriter impression position as indicated at T in Fig. 4.

A pawl 138 (Fig. 2) is pivoted on a stud 138a fixed in the pawl 72 and normally urged by a spring 139 clockwise to the position of Fig. 2 where it is stopped by engagement of a lateral lug on said pawl 138 against the pawl 72. During the counterclockwise (Fig. 2) forward stroke of movement of the shaft 71, the latter acting on the lower inclined edge of the pawl 138 merely causes the pawl 72 to rock about its pivot against the tension of the spring 76 but when the shaft 71 passes off of the shoulder 78 of the pawl 72 during the return stroke of said shaft 71, the spring 139 permits the pawl 138 to rock on its pivot 139a but the resistance of the spring slows up the return of the link 74 to normal so that the parts actuated by the link 74 are not restored too rapidly and subjected to undesirable shock when arrested in normal position.

Automatic control of safeguard printing

The operation of the safeguard character printing mechanism may be controlled so that the printing of safeguard characters to the left of amounts printed by the calculating machine printing mechanism will occur only in selected cycles of operation of the calculating mechanism. In the embodiment of the invention illustrated in the accompanying drawings the operation of the safeguard printing mechanism is controlled automatically from the traveling paper carriage so as to occur only in cycles of operation performed while the carriage is in selected columnar positions. For this purpose, the stud 75 on the pass-by pawl 72 engages in a slot in the lower end of a link 140 (Figs. 1 and 2) which is connected at its upper end to the rear end of a lever 141 pivoted at 142 on a stationary portion of the machine frame. A spring 143 connected at its upper end to the rear end of the lever 141 and at its lower end to the machine frame urges the lever 141 counterclockwise and the link 140 downwardly to the normal position shown in Fig. 1 where the shoulder 78 of the pass-by pawl 72 is raised above the path of the stud 71. In other words, the spring 143 normally holds the pass-by pawl 72 in an inactive position such that the safeguard printing mechanism

will not be operated during a cycle of operation of the calculating mechanism. The forward end of the lever 141 has a stud and slot connection with one arm of a lever 144 pivoted on a stationary portion of the machine frame. The other arm of the lever 144 carries a roller 145 which, in selected columnar positions of the carriage, is cammed upwardly by a cam plate 146 carried on the traveling carriage frame. Thus, in a selected columnar position or positions of the paper carriage, the roller 145 and thereby the link 140 are elevated to permit the spring 76 to rock the pass-by pawl to the active position of Fig. 2 where the shoulder 78 of the pawl will be engaged by the stud 71 during the return stroke of the cycle of the calculating mechanism, whereby the printing of safeguard characters to the left of the amount is effected in a manner already described.

Examples of work

Figs. 5 and 6 show, by way of example only, two examples of work which may be performed on the illustrated machine. In Fig. 5, J represents a section of a journal sheet or strip which is passed around the platen P. Also, in Fig. 5, I represents a document such as a bank check or other negotiable instrument on which a value is to be written and protected against raising by the printing of safeguard printing characters. Tabulation of the paper carriage during operations of the calculating mechanism may be controlled automatically by tabulating mechanism as illustrated in the Thieme Patent No. 1,259,929 or 1,027,225, and the return movement of the carriage may be effected by a carriage return mechanism such as that disclosed in the Thieme Patent No. 1,120,862. The value of the check or other instrument may be calculated by the machine from items entered into the calculating mechanism thereof, and the desired data involved in the calculation may be printed in one or more columns on the journal strip J. After the amount of the instrument has been entered into the machine or determined by calculating operations performed by the machine on items entered therein and the required data printed in one or more columns on the journal strip J, the paper carriage moves automatically under the control of the above tabulating mechanism to a text printing position on the check or instrument and the operator may operate the type keys 20 to type the required text, such as the value of the instrument, in words. After the typing of the text, the carriage is tabulated to position the appropriate space on the instrument for printing therein the value in figures, represented in Fig. 5 by 45.00. In the example illustrated in Fig. 5, this may be effected by a total-taking operation of the machine during which the type bars 31 for the units dollars and tens of dollars orders of the machine are indexed to their "5" and "4" printing positions, respectively, whereas the dimes and cents orders type bars as well as the hundreds of dollars and higher order type bars 31 remain in their normal "0" positions. From Fig. 3 it will also be seen that the illustrated machine has a fractional cent type bar 31f. After the type bars are appropriately indexed, the printing hammers 34 are operated to print the amount 45.00 in the space on the left side of the check I in Fig. 5 as the shaft 40 nears the end of its clockwise movement in Fig. 1 or counterclockwise movement in Fig. 2. In this position of the paper carriage

the roller 145 is elevated by the cam plate 146 so that, as the shaft 40 commences its return movement counterclockwise in Fig. 1 or clockwise in Fig. 2, the stud 71 engages the shoulder 73 of the pawl 72 and drives the link 74 rearwardly with the result that the platen is moved forwardly and the safeguard character type member 108 is positioned against the left side of the tens of dollars order type bar 31 and in front of the "0" type on the next higher order type bars 31 of the machine, after which hammer 125 is operated to print the characters **\$ on the same line as and immediately to the left of the figures 45.00 which were just previously printed on the check, after which the paper carriage may be returned across the machine by the carriage return mechanism above mentioned. To facilitate the insertion of the check forms or other instruments in printing position on the platen of the machine, the paper feeding and holding equipment of the paper carriage may be of the kind disclosed in Muller Patent 1,774,287.

Instead of using individual check forms as illustrated in Fig. 5, strips of check forms as illustrated in Fig. 6 may be employed. The test printed by the typewriting mechanism may obviously be of any desired character such, for example, as the names of payees as illustrated in Fig. 6. Likewise, the data entered on the continuous journal strip may be of any character or the journal strip can, of course, be omitted altogether.

While the preferred form of the invention as illustrated in the accompanying drawings and described hereinabove is admirably suited for the purpose indicated, it will be obvious that the invention is capable of various modifications with the scope of the appended claims.

I claim:

1. In a calculating machine having means for driving it through cycles of operation, plural order amount differential mechanism, a platen, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, said platen having a normal position where its printing line is positioned opposite the end type on said type carriers and said printing mechanism also comprising means actuated by said driving means in a machine cycle and while said platen is in its normal position to press against said platen the type positioned at said printing line on type carriers of orders corresponding to the orders of the amount printed, the combination of a special character type member mounted for movement parallel to said printing line from a normal position laterally of the highest order type carrier transversely of said type carriers and adjacent the end type of type carriers of orders higher than the highest order of an amount printed, means for shifting said platen to a position where its printing line is beyond said end type, means operated by said driving means to operate said platen shifting means to shift said platen from said normal to said shifted position and means operated by said driving means to move said special character type member transversely of said type carriers from its normal position to a position laterally adjacent the type carrier for the highest order of

the amount printed while the type carriers for the orders of the amount printed are out of their normal positions and to return said special character type member to normal, and means operated by said driving means to effect printing impression from said special character type while positioned adjacent said type carrier for the highest order of the amount printed and while said platen is in said shifted position.

- 5 2. In a calculating machine having means for driving it through cycles of operation, plural order amount differential mechanism, a platen, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, the combination of a special character type member, supporting means for said type member normally positioning said type member laterally of said type carriers and beside the highest order type carrier, means operated by said driving means to move said special character type member supporting means to shift said type member first along the side of said highest order type carrier to a point beyond the end thereof 10 when the latter has not been moved to amount printing position and then transversely of said type carriers across the ends of those for orders higher than the highest order of the amount printed to a position laterally adjacent the type carrier for the highest order of the amount printed.
- 15 3. In a calculating machine having means for driving it through cycles of operation, plural order amount differential mechanism, a shiftable platen, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, the combination of a special character type member, means for shifting said platen from a normal position where its printing line is opposite the end type on said type carriers to a shifted position where its printing line is beyond said end type, supporting means for said type member normally positioning said type member laterally of said type carriers and beside the highest order type carrier, means operated by said driving means to operate said platen shifting means to shift said platen from said normal to said shifted position and to move said special character type member supporting means to shift said type member first along the side of said highest order type carrier to a point beyond the end thereof when the latter has not been moved to amount printing position and then transversely of said type carriers across the ends of those for orders higher than the highest order of the amount printed to a position laterally adjacent the type carrier for the highest order of the
- 20 40 45 50 55 60 65 70 75

amount printed while the type carriers for the orders of the amount printed are out of their normal positions, and thereafter to return said platen shifting means and said special character type member supporting means to normal, and means operated by said driving means to effect printing impression from said special character type while the latter is positioned adjacent said type carrier for the highest order of the amount printed and said platen is in said shifted position.

4. In a calculating machine having means for driving it through cycles of operation, plural order amount differential mechanism, a shiftable platen, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, said platen having a normal position where its printing line is opposite the end type on said type carriers and said printing mechanism also comprising means actuated by said driving means in a machine cycle and while said platen is in its normal position to press against said platen the type positioned at said printing line on type carriers of orders corresponding to the orders of the amount to be printed, the combination of a special character type member, means for shifting said platen to a position where its printing line is beyond said end type, supporting means for said type member normally positioning said type member laterally of said type carriers and besides the highest order type carrier, means operated by said driving means in said machine cycle and after the printing of said amount to operate said platen shifting means to shift said platen from said normal to said shifted position and to move said special character type member supporting means to shift said type member first along the side of said highest order type carrier to a point beyond the end thereof when the latter has not been moved to amount printing position and then transversely of said type carriers across the ends of those for orders higher than the highest order of the amount printed to a position laterally adjacent the type carrier for the highest order of the amount printed while the type carriers for the orders of the amount printed are out of their normal positions, and thereafter to return said platen shifting means and said special character type member supporting means to normal, and means operated by said driving means to effect printing impression from said special character type while the latter is positioned adjacent said type carrier for the highest order of the amount printed and said platen is in said shifted position.

5. In a calculating machine having means for driving it through cycles of operation, a traveling paper carriage, a platen on said carriage, plural order amount differential mechanism, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, the combination of a special character type member mounted for movement parallel to said printing line from a normal position lat-

erally of the highest order type carrier transversely of said type carriers and adjacent the end type carriers of orders higher than the highest order of an amount printed, operating means to move said special character type member transversely of said type carriers from its normal position to a position laterally adjacent the type carrier for the highest order of the amount printed while the type carriers for the orders of the amount printed are out of their normal positions and thereafter move said type member against said platen and then return it to normal, and means controlled by said carriage to cause said operating means to be actuated by said driving means in a machine cycle.

6. In a calculating machine having means for driving it through cycles of operation, a traveling paper carriage, a platen on said carriage, plural order amount differential mechanism, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, the combination of a special character type member, supporting means for said type member normally positioning said type member laterally of said type carriers and beside the highest order type carrier, operating means to move said special character type member supporting means to shift said type member first along the side of said highest order type carrier to a point beyond the end thereof when the latter has not been moved to amount printing position, then transversely of said type carriers across the ends of those for orders higher than the highest order of the amount printed to a position laterally adjacent the type carrier for the highest order of the amount printed while the type carriers for the orders of the amount printed are out of their normal positions, and thereafter to return said special character type member to normal, means operable by said operating means to effect printing impression from said special character type while the latter is positioned adjacent said type carrier for the highest order of the amount printed, and means controlled by said carriage to cause said operating means to be actuated by said driving means in a machine cycle.

7. In a calculating machine having means for driving it through cycles of operation, a traveling paper carriage, a platen shiftably mounted on said carriage, plural order amount differential mechanism, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, the combination of a special character type member, means for shifting said platen from a normal position where its printing line is opposite the end type on said type carriers to a shifted position where its printing line is beyond said end type, supporting means for said type member normally positioning said type member laterally of said type carriers and beside the highest order type carrier, means to press said type member against said platen, operating means to operate said

platen shifting means to shift said platen from said normal to said shifted position, to move said special character type member supporting means to shift said type member first along the side of said highest order type carrier to a point beyond the end thereof when the latter has not been moved to amount printing position and then transversely of said type carriers across the ends of those for orders higher than the highest order of the amount printed to a position laterally adjacent the type carrier for the highest order of the amount printed while the type carriers for the orders of the amount printed are out of their normal positions, then operate said type pressing means prior to return to normal of the type carrier for the highest order of the printed amount, and thereafter to return said platen shifting means and said special character type member to normal, and means controlled by said carriage to cause said operating means to be actuated by said driving means in a machine cycle.

8. In a calculating machine having means for driving it through cycles of operation, a traveling paper carriage, a platen shiftably mounted on said carriage, plural order amount differential mechanism, and a plural order printing mechanism operable by said driving means in a machine cycle and comprising for each of said orders a type carrier having a longitudinal line of digit types thereon and movable from normal positions longitudinally and under control of said amount differential means to position different ones of said types at a printing line on said platen for amount printing, said platen having a normal position on said carriage where its printing line is opposite the end type on said type carriers and said printing mechanism also comprising means actuated by said driving means in a machine cycle and while said platen is in its normal position to press against said platen the type positioned at said printing line on type carriers of orders corresponding to the orders of the amount to be printed, the combination of a special character type member, means for shifting said platen to a position where its printing line is beyond said end type, supporting means for said type member normally positioning said type member laterally of said type carriers and beside the highest order type carrier, operating means to operate said platen shifting means to shift said platen from said normal to said shifted position and to move said special character type member supporting means to shift said type member first along the side of said highest order type carrier to a point beyond the end thereof when the latter has not been moved to amount print-

ing position and then transversely of said type carriers across the ends of those for orders higher than the highest order of the amount printed to a position laterally adjacent the type carrier for the highest order of the amount printed while the type carriers for the orders of the amount printed are out of their normal positions, and thereafter to return said platen shifting means and said special character type member supporting means to normal, means operated by said operating means to effect printing impression from said special character type while the latter is positioned adjacent said type carrier for the highest order of the amount printed and said platen is in said shifted position, and means controlled by said carriage to cause said operating means to be operated by said driving means after the printing of the amount in an amount printing machine cycle.

9. In a machine of the class specified, a printing mechanism comprising a series of type carriers arranged side by side, each having a series of type extending transversely of a printing line on one side thereof and terminating short of said printing line and each being movable lengthwise of said series of type, a type member, supporting means on which said type member is supported for movement parallel to said printing line, said supporting means being shiftable in a direction transverse to said printing line and parallel to said type carriers, means for moving said type member parallel to said printing line from one side of said series of type carriers toward the other side thereof, means controlling said type member moving means to position said type member normally at one side of said series of type carriers and normally holding said supporting means in a position to position said type member beside the type carrier at said one side of said series and away from said printing line, and means for operating said controlling and holding means to shift said supporting means to position said type member at said printing line, then cause said type member moving means to move said type member along said printing line toward the other side of said series of type carriers to a position adjacent the nearest type carrier positioned to place one of its type on said printing line and then cause said type member moving means to return said type member along said printing line to said one side of said series of type carriers, and then to return said supporting means to normal to return said type member to normal position out of said printing line.

HERBERT E. BROWN.
